N° 509

Patented October 12th 1852

James L. Jackson. Design for a Grate frame.

Jas. L. Jackson of New York N. Y.
Letters Patent No 509 Dated Oct 12th 1852

The schedule referred to in these Letters Patent and making part of the same

To all whom it may concern,

Be it known that I James L. Jackson of the City County and State of New York have invented or produced a new and original design for a Grate Frame and I do hereby declare the following to be a full, clear and exact description of the same reference being had to the accompanying drawing making apart thereof and which represents one half of the configuration in full, and the other half (which is precisely the same) in outline only.

The general form of the Grate frame is straight sided with a semi-elliptical top. The inner margin of the frame has a delicate bead moulding a around it, and from thence the frame rises up with a broad cavetto moulding b on which is placed scolloped work c and broad and narrow sunken ribs c d. The face or more projecting part of the frame has a base e from which rises a highly wrought half round pilaster f with a voluted cap g from which is suspended a wreath h extending down about midway of the pilaster. Above the cap is a pediment i from which the semi ellipse springs and sweeps around to the opposite side of the frame. The face of the semi ellipse has in it a sunken latticed panel j on which is placed foliated scroll work k l and the prominent centre piece is a shield m with volutes terminating in foliage. Between the pilaster and its ornaments, and the cavetto, the corner is finished with a delicate pilaster sum mounted n ornamented in a somewhat similar manner with the face pilaster with the substitution however of the pendants n for the figures K L before mentioned. The ground of the pendants is open and the cross section xx represents the general height above the frame.

Having thus fully represented the nature of my invention or design, what I claim therein as new and desire to secure by letters patent is the combination and arrangement of the ornamental figures herein represented, the whole forming an ornamental design for a grate frame.
